UNITED STATES PATENT OFFICE

2,552,192

PORTABLE ELEVATOR

Daniel L. Lawson, Los Angeles, Calif.

Application October 23, 1947, Serial No. 781,675

3 Claims. (Cl. 198—73)

1

This invention relates to improvements in portable elevators.

An object of the invention is to provide an improved portable elevator.

Another object of the invention is to provide an improved wheel-supported portable elevator which will be provided with a self-contained source of motive power for operating the same.

A further object of the invention is to provide an improved wheel-supported vehicle frame upon which a portable elevator and driving motor or engine therefor will be supported.

A still further object of the invention is to provide an improved wheel-supported vehicle upon which a vertically extending elevator shaft for a portable elevator will be mounted, together with a prime mover also mounted upon said vehicle and having means connected with said elevator shaft for operating the elevator supported thereby.

Another object of the invention is to provide an improved wheel-supported truck upon which an extendable elevator and its operating means will be supported, together with a hinged chute supported by said elevator shaft.

Another object of the invention is to provide a wheel-supported elevator and power operating means therefor which will be highly efficient in operation, and relatively inexpensive to manufacture and produce.

Other objects will appear as the description proceeds.

In the accompanying drawings which form a part of this application,

Figure 1 is a side elevation of the improved portable elevator shown in vertically extended position adjacent a building scaffold;

Figure 2 is an end elevation of the improved portable elevator shown in vertically extended position adjacent a building scaffold;

Figure 3 is a sectional view taken on the line 3—3 of Figure 7;

Figure 4 is an enlarged side elevation of the elevator shaft showing the removable guide sections supported in operative position thereon;

Figure 5 is a sectional view taken on the line 5—5 of Figure 2;

Figure 6 is a perspective view of one of the elevator boxes or containers showing a slide fixed to the said box or container;

Figure 7 is an enlarged side elevation of the elevator shaft with hinged chute supported thereby;

Figure 8 is a detail view taken on the line 8—8 of Figure 7;

2

Figure 9 is a detail plan view partly broken away and in section of the cable clamping box or container supporting shaft; and

Figure 10 is a fragmentary side elevational view of a scaffold as used with this invention.

Like characters of reference are used throughout the following specification and the accompanying drawings to designate corresponding parts.

10 In carrying out the invention, there is provided a chassis frame generally designated by the reference numeral 1 having axles 2 and supporting wheels 3. Positioning or steadyng brackets or braces 4 are hinged at 5 to the opposite ends of the chassis frame 1, and are adapted to be swung upwardly when not in use, as shown in dotted lines in Figure 1 of the drawings.

Vertically disposed standards 6 are supported by the chassis frame 1, and a horizontal platform 7 is secured to the upper ends of said standard 6.

A cylindrical metal elevator shaft 8 is supported by the platform 7 at one side thereof, being reinforced by means of the oppositely disposed vertical metal webs 9 and 10, attached to said shaft and to the framework of the platform 7.

The cylindrical metal elevator shaft 8 is provided with permanently attached oppositely disposed vertical guide rails 11 on its lower portion, and with removable lengths of guide rails 12 being detachably secured to the upper portion of the shaft 8, as clearly illustrated in Figure 4 of the drawings.

35 The opposite ends of the hollow cylindrical shaft 8 are bifurcated and support the transversely extending shafts 13 and 14 upon which the pulley wheels 15 and 16 are mounted for rotation. A continuous or endless steel cable 17 is disposed about and between the pulley wheels 15 and 16, and a sprocket wheel 18 is attached to the lower shaft 14 for rotation therewith.

A suitable motor or engine 19 for operating the elevator will be mounted upon the chassis frame 1, and will be provided with a driving sprocket wheel 20 disposed upon the motor shaft 21, the same being connected with the sprocket wheel 18 by means of the sprocket chain 22, whereby said cable 17 will be operated about the pulley wheels 15 and 16 supported at the opposite ends of said hollow elevator shaft 8.

A chute 23 having an upper section 24 hinged thereto at 25 will be attached to and supported by the metal elevator shaft 8 by means of the upper and lower bracket-supporting arms 26 and 27 respectively.

Right angularly disposed box or container trip arms 28 will be secured to the cylindrical shaft 8 in any desired position for tripping and tilting the boxes or containers 29 so that they will dump their contents down the chute sections 23 and 24 onto the scaffold 30 disposed at the side of the building 31 which is under construction.

A plurality of boxes or containers 29 will be provided and formed with solid bottoms 32, inner side walls 33, one closed or solid end 34, and a cross braced outer side wall 35, leaving one end 36 open for loading and unloading purposes.

A guide 37 which is I-shape in cross section is welded at 38 to each of said boxes or containers 29, and supports a pivot clamp 39 formed with a head 40 on its outer end and having a cable clamp 41 on its inner end for attachment to the elevator cable 17. The boxes or containers 29 are adapted to be tilted and dumped automatically by contact with the trip arms 28, and one or more L-shaped platform carriers 42 will be provided and attached to the elevator cable 17 for supporting buckets of mortar or other containers which will not be automatically dumped, since the platform carriers 42 will not be engaged by the trip arms 28.

It will be understood that the elevator will be used when constructing buildings requiring scaffolds 30 of from approximately nine feet to twenty feet in height.

A trip arm 43 will be attached to the opposite or rear lower side of the elevator shaft 8 for engaging the boxes or containers 29 as they descend the rear side of the shaft 8, for turning them upright to the correct position for re-loading.

In operation, the motor or engine 19 will be controlled by a suitable clutch (not shown) for intermittently operating the elevator cable 17 or stopping the movement of the same while the boxes or containers 29 are being loaded from the platform 7.

From the foregoing description, it will be apparent that there has been provided a highly efficient form of wheel-supported portable power-operated elevator which will be relatively inexpensive to manufacture and produce.

While the preferred embodiment of the instant invention has been illustrated and described, it will be understood that it is not intended to limit the scope of the invention thereto, as many minor changes in detail of construction may be resorted to without departure from the spirit of the invention.

Having described the invention, what is claimed as new is:

1. A portable elevator comprising a wheel-supported chassis, a loading platform supported

thereby, a vertical cylindrical metal elevator shaft supported by said platform, pulleys mounted in the opposite ends of said shaft, an endless cable entrained around said pulleys, 5 guide rails on said shaft, containers having slides supported thereon engageable with said guide rails, said slides being pivotally secured on said cable, means for driving said cable, a chute supported on said elevator shaft and having a hinged portion on the end thereof adjacent said containers, a trip on said shaft directly engaged by portions of said containers to tilt the containers toward said chute, said hinged portion of the chute being also engaged and tilted by the containers, whereby the containers are successively unloaded into said hinged portion and the hinged portion is tilted by the succeeding container for positive unloading of the hinged portion into the remaining portion of the chute.

2. The subject matter as claimed in claim 1, and including a container trip arm on said shaft adjacent said chute, and a container trip arm on a lower portion of said shaft to engage the boxes or containers and to turn them upright into position for re-loading.

3. A portable elevator comprising a wheel-supported chassis, a loading platform supported thereby, a vertical cylindrical metal elevator shaft supported by said platform, reinforcing webs attached to said shaft and platform, rotatable pulleys mounted in the opposite ends of said shaft, an endless cable about said pulleys, removable guide rails detachably secured to said shaft, containers having I-shaped slides supported upon said guide rails, cable clamping means connected between said containers and said cable, a sprocket wheel operable with said lower pulley, a prime mover on said chassis having a sprocket wheel on its shaft, and a sprocket chain connecting said sprocket wheels.
